CATHODE-RAY TUBE SUPPORT

Elmer Brinton Cain, Collingswood, N. J., assignor
to Radio Corporation of America, a corporation
of Delaware

Application January 31, 1945, Serial No. 575,497

8 Claims. (Cl. 250—141)

1

The present invention relates to supporting means for a cathode ray tube and more particularly to a novel arrangement for adjustably positioning a cathode ray tube in a television cabinet or the like.

In electrical apparatus, such as cathode ray oscilloscopes and television receivers, it is desirable to so support or mount a cathode ray tube that it may be readily installed in a cabinet in proper position with respect to a viewing aperture. Also, it is desirable to provide a support which not only holds the tube but permits adjustment of the position of the supported tube.

Accordingly, an object of the invention is to provide an improved adjustable supporting structure for cathode ray tubes.

Another object of the invention is to provide a novel combination mounting and shield for the deflecting system of a cathode ray tube.

Still another object of the invention is to provide a novel means for carrying the deflecting yoke structure of a cathode ray tube.

Other and more specific objects of the invention will become apparent from a consideration of the following specification and claims in connection with the accompanying drawings illustrating one preferred form of the invention in which:

Fig. 1 is a view in side elevation, partly in section, of the improved mounting means of the present invention, the section being taken on line 1—1 of Fig. 4;

Fig. 2 is a section of the mounting means of Fig. 1, the section being taken on line 2—2 as viewed in the direction of the arrows, certain of the parts being omitted for the sake of clearness of illustration;

Fig. 3 is a sectional view in plan, the section being taken on line 3—3 of Fig. 2 as viewed in the direction of the arrows;

Fig. 4 is a view in front elevation of the cabinet fragmentarily shown in Fig. 1; and

Figs. 5 and 6 are elevational views of a detail of the device shown in Figs. 1 and 4.

Referring to the drawings, and for the present more particularly to Figs. 1 and 4 thereof, a housing cabinet 10 for electrical apparatus, for example a television receiver adapted to incorporate a cathode ray tube, is shown. A cathode ray tube, shown only in outline form for the sake of convenience of illustration since it is a replaceable element and may vary in shape and/or size, is indicated by reference character 12 and comprises a substantially flat target or screen end 14 provided with the usual luminescent screen or other viewing means, a flare or bulb portion 16, a neck

2

portion 17, and a base 18 from which projects the terminal connectors or pins 22. When a cathode ray tube is supported in accordance with the invention disclosed herein, the tube socket (not shown) which engages the pins 22 may be attached to the ends of a flexible cable suitably connected to the circuits of the apparatus housed in the cabinet 10.

The cabinet 10 presents a panel 24 having an opening 26 which for the usual type of cathode ray tube will be circular. However, it will be understood that the opening 26 will have a configuration to suit the tube 12 employed. The panel 24 may be a unitary part of the cabinet 10 if desired. A removable panel or cover 28 having a viewing opening 31 is secured against the panel 24 by suitable fastening means such as screws 32. These screws may be located anywhere so as to hold the cover 28 in position, but for the sake of symmetry of appearance four of these screws are shown in Fig. 4 of the drawing. The opening 31 may be fitted with a pane of safety glass or a transparent plastic depending upon the type of tube used.

25 The bulb portion 16 of the tube 12 is positioned in the opening 26 and behind the opening 31 by adjustable brackets 33 which are shown in detail in Figs. 5 and 6 of the drawings. For the usual circular cathode ray tube supported before a viewing opening such as 31 in the cover 28, the brackets 33 are preferably arranged radially as shown in Fig. 4 of the drawings.

Each bracket 33 is of channel form for at least a portion of its length and so has side walls 36 and is provided with a slot 37 for adjustably receiving a fastening means such as a bolt or screw 39 (Figs. 1 and 4). The channel shape of the bracket prevents the securing nut 38 (Fig. 1) from rotating so that the bracket may be adjusted from 40 the front of the panel 24 by applying a tool, such as a screwdriver, to the screw 39. The bent tongue 42 of the bracket is or may be shaped to conform somewhat to the shape of the bulb 16 of the tube 12. This is indicated by way of example in Fig. 5 45 of the drawings. Recesses 34 provide clearance between the tongues 42 and the tube. A tang 43 is bent down from the body of the bracket 33 so that it assists in retaining the bracket in position against the panel 24 when the associated screw 50 39 is tightened in the nut 38 into which it is threaded.

In the receiver illustrated, the cathode ray beam of the tube 12 is deflected by means of a deflecting coil unit or yoke indicated by reference character 44. This yoke may be of any

suitable construction but preferably is of the type described and claimed in application for Letters Patent of the United States, Serial No. 575,369, filed January 31, 1945, in the name of Charles Edward Torsch. In the yoke of the Torsch application, end rings 46 and 48 form a part of the yoke structure and provide a convenient means for carrying a cross bar member 50 (Figs. 2 and 3). The wire 53 forming the iron sheath of the yoke 44 is or may be grounded on the bar 50 for the purpose explained in the Torsch case referred to above. The cross bar member is provided with a longitudinal slot 54 which may be of any length desired, depending upon the desired range of adjustment.

A bracket member 56, which serves as a support as well as a shield for the yoke 44 and the neck portion 17 of the tube 12, is secured in any suitable manner, such as by screws, indicated at 58 to a support such as top plate 60 appearing fragmentarily in Figs. 1 and 2 of the chassis (not shown) of the apparatus in which the tube 12 is employed. The flange 61 is preferably slotted as indicated at 63 to provide for longitudinal adjustment, bodily, of the bracket member 56 for a reason which will appear later herein. A separate apron or brace 59 (best shown in Fig. 2) extends beneath the bulb 16 of the tube 12. The bracket 56 is provided with a yielding guard member 62 of rubber or the like which engages the glass part of the tube. A similar guard 64 is placed over the exposed rim of the brace 59.

The cross bar 50 has down-turned sides 65 so that it is channel shaped to accommodate a nut 66. This nut, for convenience, may be channel shaped as shown and is provided with an internally threaded aperture 71. The downwardly turned sides 66 of the bar 50 prevent the nut 66 from rotating. A transverse slot 72 is provided in the bracket 56, and slots 54 and 72 combine to give two ranges of adjustment to the yoke 44 and hence the tube 12. A wing screw 74 is threaded into the aperture 71 in the nut 66 to complete the assembly. Rotation of the yoke 44 in the bracket member 56, which is provided for by the slot 72, affords a convenient means for leveling the image at the end 14 of the tube 12 after the tube is placed in the manner hereinafter pointed out, and is especially useful where the face 14 of the tube has a mask painted or otherwise affixed therein or thereon.

From the foregoing description of the mounting means of the present invention, it will be seen that a complete mounting as well as a convenient viewing arrangement of neat appearance is provided for the cathode ray tube 12. In assembling the parts initially or for the purpose of replacing the tube 12, the yoke 44 is first positioned within the bracket 56 by means of the wing screw 74 and the nut 66. The cover 28 is removed and the tube is passed through the opening 26 so that the neck 17 projects through the tube accommodating opening in the yoke 44.

The screws 39 will be loosened so that the brackets 33 are in a non-interfering position when the bulb is inserted, following which the end face of the tube 12 is brought to the proper position by adjusting the brackets 33. Marks (not shown) may be located on the panel to facilitate positioning of the tube. Wing screw 74 is loosened and left in that condition until after pressure has been established on the bulb.

portion 16 of the tube 12 by yielding guards 62 and 64.

Pressure on the tube 12 is established by loosening the screws 58 and sliding the bracket 56 forward and retightening screws 58. This sliding movement of the bracket member 56 is permitted by the slots 63. The front face of the tube is held by the lips 42 on brackets 33. In the case of a so-called round faced (dished front) tube pressure may be exerted directly on the panel 28 instead of the lips of brackets 33. A pad or packing 81 of yielding material such as rubber may be provided for cushioning the face 14 of the tube 12 where it is close to or is pressed toward and into contact with the panel 28.

With the tube in position as just explained, the screw 74 may then be loosened so that the yoke 44 may be moved toward the panel 26, possibly touching the bulb 16 of the tube 12 with the coil ends 79. The wing screw 74 is then retightened.

It will be understood that the tube supporting means of this invention is also applicable to the support of television camera tubes of various types, and therefore, the term "target" as used in the claims herein will be understood to refer to a cathode ray tube element such as a luminescent screen or other viewing device, or a mosaic element or the like of a camera tube.

Various alterations may be made in the present invention without departing from the spirit and scope thereof, and it is desired that any and all such alterations be considered within the purview of the present invention as defined by the hereinafter appended claims.

Having now described the invention, what is claimed and desired to be secured by Letters Patent is the following:

40. 1. Cathode ray tube apparatus in which is to be mounted a cathode ray tube comprising an evacuated envelope, a panel having an opening therein, a plurality of brackets located around said opening and being adjustably mounted in the panel adjacent thereto so as to hold an end of said tube in a predetermined position in said opening, means serving as a stop to position the tube longitudinally, and supporting means providing support for the tube at a point remote from the brackets and being capable of exerting pressure on the tube in a direction longitudinally thereof and toward the stop means.

55. 2. Cathode ray tube apparatus comprising a housing in which is to be mounted a cathode ray tube having an evacuated envelope which is provided with a target element at one end thereof, the housing having a panel with an opening therein sufficiently large to admit the tube, a plurality of brackets located around said opening and being adjustably mounted on the panel adjacent to the edge of the opening so as to hold the target end of said tube in a predetermined position in said opening, and supporting means providing support for the neck of the tube and being capable of exerting pressure on the tube in a direction longitudinally thereof and toward the panel.

70. 3. Cathode ray tube apparatus comprising a housing in which is to be mounted a cathode ray tube of the type comprising an evacuated envelope which is provided at one end with a target, the housing comprising a panel with an opening therein large enough to admit the tube, a plurality of brackets located around said opening and being adjustably mounted on the panel.

adjacent to the edge of the opening so as to hold the target end of said tube in a predetermined position in said opening, a deflecting coil yoke mounted in the housing with an opening therein in line with the opening in the panel whereby the tube may be moved into the cabinet from in front of the panel into position where the neck of said tube passes through the yoke, and supporting means carrying said yoke in a manner to permit said yoke to be movable toward said panel whereby the yoke is seated on the tube neck in a position to provide efficient deflection.

4. Cathode ray tube apparatus comprising a housing in which is to be mounted a cathode ray tube having an evacuated envelope which is enlarged at one end, the housing having a panel with an opening therein sufficiently large to admit the large end of the tube, a plurality of brackets located around said opening and being adjustably mounted on the panel adjacent the edge of the opening so as to hold the enlarged end of said tube in a predetermined position in said opening, supporting means providing support for the neck of the tube and being capable of exerting pressure on the tube in a direction longitudinally thereof toward the panel, a removable panel having an opening therein of a size to mask all but the portion of the tube which presents an image to be viewed, and means for securing said removable panel in front of the first named panel with the masking openings in position to expose the viewing face of the tube.

5. In cathode ray tube apparatus of the type in which a cathode ray tube is held in a predetermined position at its target end, means to provide additional support for the tube at a location spaced from the target end comprising a deflecting coil yoke having an opening therein to receive the neck of the tube, carrying means for said yoke comprising a support member and a connection between said support member and said yoke which is adjustable both longitudinally and transversely of the yoke.

6. In cathode ray tube apparatus comprising a deflecting coil yoke, a mounting for said yoke comprising a member secured to the yoke and having a slot therein which extends longitudinally of the yoke a carrying member secured to a fixed part of the cathode ray tube apparatus and having a slot therein transversely of the axis of the yoke, and clamping means passing through both of said slots whereby upon loosening said clamping means said yoke may be moved for adjustment in two directions substantially at right angles to each other.

7. Cathode ray tube apparatus comprising a housing in which is to be mounted a cathode ray tube of the type comprising an evacuated envelope with a connecting base at one end and a

target device adjacent the other end, the housing comprising a panel having an opening therein of a diameter greater than the diameter of the tube, a plurality of brackets located around said opening each bracket including a channel portion and a tube positioning tongue, the channel portion having an elongated slot, a screw for each bracket projecting through said elongated slot, a nut for each screw in the channel portion of each bracket, said panel having screw receiving apertures adjacent to its tube receiving opening so that the end of said tube is held in said opening in a position determined by the adjustment of said brackets, a deflecting coil yoke mounted in said housing with an opening therein in line with said opening in the panel whereby the tube may be moved into the housing through the panel into position with the tube passing through said yoke, and supporting means carrying said yoke in a manner to permit said yoke to be movable toward said panel whereby said yoke exerts pressure longitudinally of the tube to hold the same in position in the tube positioning tongues of said brackets with the base end of the tube free.

8. Cathode ray tube apparatus of the type in which the cathode ray tube is held in a predetermined position at its target end, means to provide additional support for the tube at a location spaced from the target end comprising a deflecting coil yoke having an opening therein to receive the tube, carrying means for said yoke comprising a support member having a slot therein transversely of the yoke, a member on said yoke having a slot longitudinally of the yoke, and screw means passing through said slots, said yoke thereby being adjustable in two directions with respect to said support member.
